Edward Weston,
BY *Clark Benjamin,*
His ATTORNEY,

UNITED STATES PATENT OFFICE.

EDWARD WESTON, OF NEWARK, NEW JERSEY.

GALVANOMETER.

SPECIFICATION forming part of Letters Patent No. 392,478, dated November 6, 1888.

Application filed August 17, 1888. Serial No. 282,990. (No model.)

To all whom it may concern:

Be it known that I, EDWARD WESTON, of Newark, Essex county, New Jersey, have invented a new and useful Improvement in Galvanometers, of which the following is a specification.

My invention relates to electrical measuring apparatus, and more particularly to galvanometers wherein are contained a magnet and suspending-fiber, the magnet being provided with a mirror, from which a beam of light is reflected upon a suitable scale.

My invention consists in the construction hereinafter described and claimed.

15 In the accompanying drawings, Figure 1 is a vertical transverse section, and Fig. 2 is a side elevation, of a portion of a galvanometer containing my invention. Figs. 3 and 4 are similar views, respectively, to Figs. 1 and 2, showing a modification of the device.

Similar letters of reference indicate like parts.

A is a cylindrical shell having an aperture forming a ring-seat for the reception of the spools D and E, which carry the coils. Said shell is supported upon the pillar B, and above it is the tube C, said shell, pillar, and tube forming parts of the standard of the instrument.

25 The outer flanges, *a b*, of the spools D E are provided with shoulders which fit over the exterior rims of the spools D E. The inner flanges of the spools D E do not meet when the spools are in place in the shell; but there is a space or interval left between them, through which and through the tube C passes the suspending-fiber F of the magnet-needle G. The cores of the spools D E are tubular, as shown.

35 Referring more particularly to Figs. 1 and 2, H is a short section of tube threaded at one end and screwed into the inner extremity of the core of spool D. The other end of tube H is inserted in the inner extremity of the core of spool E. In the side of tube H is a longitudinal slot, I, through which passes the filament F. The tube H forms a chamber for the reception of the needle G.

40 Into the outer ends, respectively, of the cores of the spools D E are inserted short tubes J, each being flared or enlarged outwardly and covered or closed with plates K, of glass or other translucent material. The tubes J may be shouldered in the correspondingly-formed core-openings, as shown in Fig. 1.

Passing through the outer flanges of the spools D E are set-screws L, which enter the rims of the shell A, and thus secure the spools 55 in place in said shell.

The parts above described are assembled as follows: The needle G being suspended in the shell A, the spool D, with the tube-section H in place, is inserted in the shell (the fiber F entering the slot I) until the shoulder on its flange *a* meets the rim of the shell, when the screws L are inserted and set up. The other spool, E, is then placed in the shell, its hollow core receiving and sliding over the end of tube H, 65 and this is secured in like manner in said shell by screws L. In the modification of the device shown in Figs. 3 and 4 the tube H is made in two portions, N N', each of which is provided with a flange or collar, *i i'*, which extends 70 over the faces of the inner flange of the spools D E. A radial slot, *j*, is formed in each collar *i i'*. When the spools D E are placed in the shell A, the collars or flanges *i i'* meet to form a spacing-disk, which comes between the faces 75 of the spool-flanges, and the slots *j* coincide to form a channel through which the filament F passes.

At M are binding-screws, to which the coil-terminals are secured. A mirror attached to 80 the needle G may be observed through the glass plates or covers K, or a beam of light from said mirror may be reflected through said plates upon a scale in the usual way.

I claim—

1. In an electrical measuring-instrument, a standard having a ring-seat, two spools carrying coils and received in said seat, so that a space or interval is left between the inner faces of said spools, and a magnet suspended in 90 said interval between the centers of said spools, substantially as described.

2. In an electrical measuring-instrument, a standard having a ring-seat, two spools carrying coils adapted to enter said seat and having tubular cores, and a short tube entering the inner ends of said cores when said spools are in place in said seat, substantially as described.

3. In an electrical measuring-instrument, a 100 standard having a ring-seat, a spool carrying a coil adapted to enter said seat and having a tubular core, and a tube entering and sliding freely in said core and closed at its end, by

glass or other translucent material, substantially as described.

4. In an electrical measuring-instrument containing a magnet-needle and a suspending filament therefor, a standard having a ring-seat, two spools carrying coils adapted to enter said seat and having tubular cores, and a short tube entering the ends of said cores and having a longitudinal slot in its wall or side, 5 the said filament extending through a space or interval between the faces of the inner flanges of said spools and through said slot and supporting said magnet within said tube, substantially as described.
- 10 5. In an electrical measuring-instrument, the combination of the standard having the cylindrical shell A, spools D E, having wide outer flanges to extend over the rims of said shell and carrying coils, and screws L, securing said flanges to said rims, substantially as described.
- 15 6. In an electrical measuring-instrument, the combination of the standard having the

cylindrical shell A, spools D E, carrying coils and having tubular cores, magnet G, and filament F, substantially as described. 25

7. In an electrical measuring-instrument, a standard having a ring-seat, two spools carrying coils adapted to enter said seat, and means for securing the outer flanges of said spools 30 directly to the exterior rims or faces of said seat, substantially as described.

8. In an electrical measuring-instrument, a standard having a ring-seat, two spools carrying coils adapted to enter said seat, and means 35 for securing the outer flanges of said spools directly to the exterior rims or faces of said seat, the axial length of the said spools being such that a space or interval is formed between said spools when the same are in place in said 40 seat, substantially as described.

EDWARD WESTON.
